CLAIM

The ornamental design for a basket for a frame of built-in home appliances, as shown and described.

DESCRIPTION

FIG. 1 is a front perspective view of a basket for a frame of built-in home appliances showing our new design;

FIG. 2 is a front view thereof;

FIG. 3 is a rear view thereof;

FIG. 4 is a left side view thereof where the right side view is a mirror image;

FIG. 5 is a top plan view thereof where the bottom plan view is a mirror image;

FIG. 6 is a back perspective view thereof;

FIG. 7 is an exploded view thereof;

FIG. 8 is a cross-section view taken along the line "8-8", as shown in FIG. 2;

FIG. 9 is a perspective view for reference, showing where the claimed design would mount in an environment of use;

FIG. 10 is another perspective view for reference, showing the claimed design mounted in an environment of use; and, FIG. 11 is a reference enlarged view of the part of the left side of FIG. 10.

The broken lines depict portions of the basket for a frame of built-in home appliances that form no part of the claimed design. The dash-dot broken lines define the boundary of the claimed design and form no part thereof. The broken lines
